US0D1064384S

(12) **United States Design Patent** (10) **Patent No.:** **US D1,064,384 S**
(45) **Date of Patent:** **** Feb. 25, 2025**

(54) **PROJECTION SYSTEM**

(71) Applicant: **BlissLights LLC**, Oceanside, CA (US)

(72) Inventors: **Masoud Ghorani**, Lake Forest, CA (US); **Randy E. Johnson**, Vista, CA (US)

(73) Assignee: **BlissLights LLC**, Oceanside, CA (US)

(**) Term: **15 Years**

(21) Appl. No.: **29/840,044**

(22) Filed: **May 25, 2022**

(51) LOC (15) Cl. **26-05**

(52) U.S. Cl. **D26/104**
USPC ....

(57) **CLAIM**

The ornamental design for a projection system, as shown and described.

DESCRIPTION

FIG. 1 is a front top perspective view of a first embodiment of a projector of the projection system;

FIG. 2 is a rear bottom perspective view thereof;

FIG. 3 is a front view thereof;

FIG. 4 is a rear view thereof;

FIG. 5 is a left-side view thereof;

FIG. 6 is a right-side view thereof;

FIG. 7 a top view thereof; and

FIG. 8 is a bottom view thereof.

FIG. 9 is a front top perspective view of a second embodiment of a projector of the projection system;

FIG. 10 is a rear bottom perspective view thereof;

FIG. 11 is a front view thereof;

FIG. 12 is a rear view thereof;

FIG. 13 is a left-side view thereof;

FIG. 14 is a right-side view thereof;

FIG. 15 a top view thereof; and,

FIG. 16 is a bottom view thereof.

The broken lines showing portions of the projection system form no part of the claimed design.

1 Claim, 16 Drawing Sheets
